CONVERSION OF HYDROCARBONS

Don R. Carmody, Hammond, Ind., assignor to
 Standard Oil Company, Chicago, Ill., a corpora-
 tion of Indiana

No Drawing. Application March 28, 1940.
 Serial No. 326,468

2 Claims. (CL 260—683.4)

This invention relates to a process for the production of high octane number liquid hydrocarbons from hydrocarbons of lower molecular weight and relates more particularly to a process for the interaction of paraffinic hydrocarbons for the production of normally liquid hydrocarbons suitable for aviation gasoline.

It is an object of this invention to provide a process wherein paraffinic hydrocarbons, and particularly isoparaffinic hydrocarbons, are reacted to form isoparaffinic hydrocarbons of higher molecular weight. Another object of this invention is to provide a process wherein isoparaffinic hydrocarbons of low molecular weight are reacted in the presence of an alcohol. It is a further object of this invention to provide a process for the production of high octane number gasoline by the condensation of isoparaffinic hydrocarbons having at least four carbon atoms per molecule in the presence of a promoter such as an alcohol. Further objects and advantages will become apparent as the description of my process proceeds.

The alkylation of hydrocarbons, particularly isobutane and isopentane with olefins in the presence of sulfuric acid for the production of high octane number hydrocarbons falling within the gasoline boiling range is well known. In alkylation reactions the molar ratio of isoparaffin to olefin reacting is always 1:1 or less. This is obvious when it is remembered that one mol of isoparaffinic hydrocarbon reacts with one mol of olefinic hydrocarbon to form one mol of isoparaffinic hydrocarbon of higher molecular weight. In the event that the higher isoparaffinic hydrocarbon formed is further alkylated under certain circumstances with an additional mol of olefinic hydrocarbon, the molar ratio of original isoparaffinic hydrocarbon to olefinic hydrocarbon is reduced to less than 1:1. I have discovered, however, that by carrying out the process under similar conditions in the absence of olefins but with the addition of an alcohol that paraffinic hydrocarbons having an isomeric configuration can be made to react in such manner that more than one mol of isoparaffinic hydrocarbon reacts per mol of alcohol with the formation of higher boiling liquid hydrocarbons characterized by high octane number. During the process the alcohol is simultaneously converted to a paraffinic hydrocarbon which can be separated from the product or can be left blended therewith if desired, in order to provide a balanced fuel suitable both in boiling range and octane number for use in aviation engines.

As an example of my process, 280 parts by weight of isobutane was mixed by violent agitation with 423 parts by weight of 98.6% sulfuric acid to form an emulsion at a temperature of about 70 to 80° F. An inert diluent, normal heptane, was added to lower the vapor pressure of the isobutane. To the emulsion thus formed was added 101 parts by weight of tertiary amyl alcohol, the addition being made over a period of approximately 3 hours. The reaction was carried out over a total period of 6.25 hours. A total of 161 parts by weight of product boiling above pentanes was produced. The weight percent yield of product, exclusive of unreacted feed stock, was 200% based on the potential olefin in the alcohol which was distributed as follows:

Fractionation of product:

	Vol. %
C ₆	16.0
C ₆	7.8
C ₇	3.9
C ₈	48.6
C ₉	7.3
C ₁₀	6.8
C ₁₁₊	9.6

An amount of normal heptane equivalent to that added as inert diluent was recovered from the C₇ cut. The data have been corrected for this. A parallel run was made with the same amount of tertiary amyl alcohol and normal heptane at the same operating conditions but in the absence of an isoparaffinic hydrocarbon. The normal heptane was recovered quantitatively, thus indicating that this diluent is inert in the above example.

All products were completely saturated. It will be noted that the primary products from the reaction are pentanes and octanes. Ordinarily it would be expected that "alkylation" would take place between the isobutane and the tertiary amyl alcohol with the formation of an isononane and the elimination of water. In place of this it appears from the distribution of the products that the isobutane has reacted with itself with the formation of isoctane and that the tertiary amyl alcohol has been converted to isopentane. This is further emphasized by the fact that in this example 2 mols of isoparaffin per mol of alcohol reacted, and that a corresponding amount of isopentane was produced.

Although I do not intend to be restricted to any particular theory as to the mechanism by which this reaction takes place, it is my suggestion that under the conditions set forth hy-

drogen or a hydrogen radical, or a proton is removed from the isobutane, and used for the hydrogenation of the tertiary amyl alcohol with the accompanying production of water therefrom. The dehydrogenated isobutane either simultaneously or subsequently interacts to form an isoctane.

A similar experiment was carried out employing 319 parts by weight of isopentane and 580 parts by weight of 98.6% sulfuric acid. In this case no inert diluent was used. Over a period of 5.3 hours 75 parts by weight of tertiary butyl alcohol was added at a temperature of 70° to 80° F. and the reaction continued for a total period of 6 hours. Product equivalent to 237 parts by weight, exclusive of unreacted feed stock, was obtained giving a weight yield of 423% based on the potential olefin in the alcohol. In this case 2.7 mols of isopentane per mol of alcohol reacted.

The product consisted of 65 parts by weight of isobutane and 172 parts by weight of hydrocarbons (exclusive of the unreacted isopentane) boiling in the gasoline range. The higher boiling hydrocarbons showed the following distributions:

Fractionation of product:	Vol. %
C ₆	23.4
C ₇	3.2
C ₈	23.4
C ₉	21.5
C ₁₀	22.6
C ₁₁₊	5.9

All products were completely saturated.

In this case it will be noted that there is a more even distribution of products between the hexanes, octanes, nonanes and decanes which is believed to be due to the tendency of the decanes which would be formed by the interaction of the isopentane to break down under the conditions employed here into C₆ and C₄ hydrocarbons. The isobutane produced from the butanol or from the disproportionation of the decane may then react to produce C₈.

A run employing secondary butyl alcohol and isopentane was carried out as follows:

424 parts by weight of 98.6% sulfuric acid, 314 parts by weight of isopentane and 73.5 parts by weight of secondary butyl alcohol were reacted as described above at 70-78° F. for 6.25 hours to yield 42 parts by weight of isobutane and 144 parts by weight of hydrocarbons boiling in the gasoline range exclusive of unreacted isopentane. This represents a yield of 334% by weight based on the potential butylene in the alcohol, and corresponds to 2.2 mols of isoparaffin per mol of alcohol reacting. The gasoline hydrocarbons had the following distribution:

	Vol. %
C ₆	22.7
C ₇	0
C ₈	0
C ₉	50.0
C ₁₀₊	27.3

All products were completely saturated. In this case it should be noted that the product from the conversion of secondary butyl alcohol to the paraffin was not normal butane as might be expected, but isobutane, indicating an isomerization side-reaction.

In carrying out my process the alcohol may be obtained from suitable sources and may advisably be procured by the absorption of olefin-contain-

ing gases in dilute sulfuric acid with subsequent further dilution to separate out the alcohols formed thereby and recovery of the alcohol by distillation. I prefer to use alcohols and isoparaffinic hydrocarbons having four or five carbon atoms per molecule since in employing these hydrocarbons as reactants the reaction product boils primarily within the gasoline boiling range found most suitable for use in aviation gasoline which requires high octane number fuels. For the production of higher molecular weight products such as aviation safety fuel, a feed material consisting of isoparaffinic hydrocarbons having a molecular weight of 86 or higher should be used.

Broadly speaking, my process may be carried out at temperatures limited only by freezing temperature of the sulfuric acid as the lower limit, and the oxidation of the hydrocarbons by the sulfuric acid as the upper limit. A range from about 10° F. to 110° F. is permissible, and, preferably, I may use a temperature of from about 30 to about 80° F. Sulfuric acid having an acidity of from 85% to 101%, preferably about 96%, is a suitable catalyst for my process. It is desirable in all cases that sufficiently violent agitation be used to insure intimate contact between the reactants and the catalyst. This may be accomplished by stirring mechanisms, by jet injectors, or by any other suitable mechanical means. An inert diluent may be employed to reduce the vapor pressure of the reactants or the reactants may be maintained in the liquid phase by superatmospheric pressure. The presence of inert gases, such as normal paraffins which are ordinarily found mixed with isoparaffins in hydrocarbons from such sources as the crack'ng of petroleum and in natural gas or casinghead, is not objectionable, altho, since they do not enter into the reaction, they are not desirable. I prefer to carry out the reaction using an excess of isoparaffinic hydrocarbons above that theoretically necessary to react with the alcohol. There should be present at least two mols of isoparaffin for every mol of alcohol, and preferably more than two mols of isoparaffin for every mol of alcohol.

It has been found that isopropyl alcohol is not effective for my process, which I have designated dehydroalkylation. When using isopropyl alcohol a direct reaction between the alcohol and the isoparaffin is obtained with the formation, for example, of isoheptane, when using isobutane with isopropyl alcohol.

When employing a butyl alcohol in my process one of the primary products is isobutane which can be utilized in a corresponding dehydroalkylation reaction employing an alcohol of four or more carbon atoms or it may be fittingly employed in an alkylation reaction using isopropanol and an isoparaffin as the feed. When using tertiary amyl alcohol in my process, the isopentane formed can be retained in or suitably blended with the dehydroalkylation product since generally it is desirable to increase the volatility of the aviation fuel, and isopentane has a sufficiently high octane number to render its presence valuable in the production of an aviation gasoline.

Since by my process a certain amount of water is formed as a by-product, this will necessarily dilute the sulfuric acid catalyst below reaction strength so that in a continuous or batch process it is desirable to restore the original acidity by concentration or by fortification with sulfur trioxide or fuming sulfuric acid. The diluted acid can also well be employed in a polymerization

process in which olefinic gases are converted to di- and tri-olefins in the presence of dilute sulfuric acid or if sufficiently diluted, the acid can be directed to an alcohol-producing unit for absorption of olefins and the formation of alcohol suitable for use in my process. Further modification and extrapolations of my process will readily occur to one skilled in the art.

My process is notable in that it is ordinarily considered, thermodynamically, that two paraffin molecules cannot form a higher paraffin by the elimination of a molecule of hydrogen. By my process, however, a "hydrogen acceptor" is provided, which furnished a means whereby the hydrogen apparently can be withdrawn from the reaction, leaving the dehydrogenated paraffins available for reaction. In spite of this hypothesis, however, it is indeed surprising that more than one mol of isoparaffinic hydrocarbon reacts per mol of alcohol rather than one mol or less of the isoparaffin feed stock reacting with each mol of olefin as in the case of the well-known alkylation processes.

It should also be pointed out that by my process hydrocarbons of gasoline-like properties characterized by high octane numbers are produced with greater yields than the usual commercial synthesis, and without the necessity for involved recycling in order to utilize as far as possible the available paraffinic feed stock.

30

carbon from isoparaffinic and olefinic hydrocarbons, the steps of absorbing olefin-containing gases in dilute sulfuric acid, diluting the sulfuric acid further to separate out the alcohols, contacting the resulting alcohols with said isoparaffinic hydrocarbons in the presence of concentrated sulfuric acid at a temperature whereby a higher molecular weight saturated hydrocarbon and water are produced thereby diluting the sulfuric acid and supplying the diluted sulfuric acid to the first-mentioned absorption step.

2. In a process of producing a saturated hydrocarbon boiling in the gasoline range from isoparaffinic and olefinic hydrocarbons having more than three and less than six carbon atoms per molecule, the steps of absorbing the olefinic hydrocarbons in dilute sulfuric acid, diluting the combined stream of absorbed olefins and sulfuric acid to recover the corresponding alcohols, contacting the isoparaffinic hydrocarbons and said alcohols in the presence of sulfuric acid having an acidity of between about 85 and about 101% at a temperature of between about 30 and 80° F. to produce isoparaffinic hydrocarbons boiling in the gasoline range, a saturated hydrocarbon corresponding to the alcohol and water, recovering the resultant diluted sulfuric acid and supplying the diluted acid to the first mentioned olefin absorption step.

DON R. CARMODY.

I claim:

1. In a process of producing a saturated hydro-
